UNITED STATES PATENT OFFICE.

FREDERICK L. FULLER, OF BRIDGEPORT, CONNECTICUT, ASSIGNOR TO THE NATIONAL CASH REGISTER COMPANY, OF DAYTON, OHIO.

MACHINE FOR PRINTING AND ISSUING RAILWAY-TICKETS.

1,392,929.

Specification of Letters Patent.

Patented Oct. 11, 1921.

Original application filed October 27, 1916, Serial No. 128,093. Divided and this application filed December 18, 1919. Serial No. 345,826.

To all whom it may concern:

Be it known that I, FREDERICK L. FULLER, a citizen of the United States, residing at Bridgeport, in the county of Fairfield and State of Connecticut, have invented certain new and useful Improvements in Machines for Printing and Issuing Railway-Tickets, of which I declare the following to be a full, clear, and exact description.

10 This invention relates to ticket issuing machines and has more particular relation to that class of ticket issuing machines adapted for use in issuing tickets for railroad and steamship lines or other analogous uses.

15 The subject matter of the present application constitutes a division of an application of Frederick L. Fuller, Serial No. 128,093, filed October 27, 1916.

20 Certain of the constructions shown in the present application are not described in detail and claimed herein as it is sought to cover those constructions in the parent application and reference may be had to the same for a detailed description of those 25 mechanisms.

The general object of this invention is to provide an improved compact and efficient machine for use in ticket offices of railroads, steamship lines and other lines of 30 travel to issue tickets of different classes and accurately account for the money received for the tickets of each class, (such as "full fare round trip," "full fare one way," "half fare round trip," "half fare one way," 35 "excursion" and "clergyman") to each station as well as for the total amount received for all of the tickets issued by the machine. It will be apparent that the invention is 40 capable of use in other embodiments without constituting departure from the scope of the present invention.

One of the principal objects of this invention is to provide improved destination devices constructed to print the names of the 45 destination stations and the classes on the tickets, retain records of the number of tickets of each class issued to each station and control the numbering of and the printing of the values on the tickets. In the 50 present embodiment but one destination device is provided for each station taken care of by the machine. Each destination device is adapted to print the name of the destination station, the classes of the tickets and

any other desired information as well as 55 control the printing of the number and value of the ticket of each particular class. In some inventions relating to railroad ticket machines one destination device is provided for each class of tickets to each 60 station instead of for all classes of tickets to each station and therefore the number of destination devices is greatly increased. It is evident that in such inventions the destination devices require more space and their 65 selection is more tedious and requires more time.

A further object of the invention is to provide improved means for selecting the desired destination devices for use and moving it into position to print a ticket of the desired class. In the illustrative form of embodiment the destination devices are carried on an endless chain, which is adjusted to move the desired destination device into 75 position to be inserted into the printing mechanism. Then a foot pedal, appropriate to the desired class of ticket, is operated to move the selected device into the printing mechanism so that the ticket of the desired 80 class is printed and issued.

With these and incidental objects in view, the invention consists in certain novel features of construction and combinations of parts, the essential elements of which are 85 set forth in appended claims, and a preferred form of embodiment of which is hereinafter described with reference to the drawings which accompany and form part of the specification.

90 Of said drawings:

Figure 1 is a perspective view of the machine embodying the present invention.

Fig. 2 is a detail sectional view taken on the line 2—2 of Fig. 6^B and shows the lower 95 pair of sprocket wheels in full.

Fig. 3 is a detail sectional view taken on the line 3—3 of Fig. 2 and shows the devices for preventing operation of more than one foot pedal at a time.

Fig. 4 is a detail sectional view taken on the line 4—4 of Fig. 6^A.

Fig. 5 is a detail vertical section taken on the line 5—5 of Fig. 4.

Figs. 6^A and 6^B combined constitute a detail left hand side view of the machine with part of the cabinet shown in cross section.

Figs. 7^A and 7^B combined constitute a

transverse vertical section taken through the center of the machine. The portion of the cabinet covering the printing and totalizing mechanisms is shown in full and the chain carrying the destination devices is shown in side elevation instead of in section.

Fig. 8 is a horizontal sectional view taken on the line 8—8 of Fig. 6^A.

Fig. 9 is a detail horizontal sectional view 10 taken on the line 9—9 of Fig. 6^B.

Fig. 10 is a detail horizontal sectional view taken on the line 10—10 of Fig. 6^B, but shows the upwardly extending arms of the levers carrying the foot pedals in full.

Fig. 11 is a full sized detail side view of 15 a portion of the chain carrying the destination devices and shows one of the destination devices in position in one of the links of the chain.

Fig. 12 is a full sized detail top plan view 20 of one of the destination devices, with one of the printing plates removed.

Fig. 13 is a full sized detail front view 25 of one of the destination devices.

Fig. 14 is a full sized detail side view 30 of part of the means for moving the selected destination device into printing position.

Figs. 15 and 16 respectively are full sized 35 rear and top plan view of the means shown in Fig. 14.

Fig. 17 is a full sized section taken 40 through the slides shown in Figs. 14, 15 and 16. The section is taken on the line 17—17 of Fig. 14 and shows the slides extended.

Fig. 18 is a full sized top plan view of 45 the means for locking the slides shown in Fig. 17 in adjusted positions.

Fig. 19 is a full sized view of a portion of 50 the detail strip used in the machine and shows a detail record of the tickets as issued.

Fig. 20 is a full sized view of a portion 55 of the detail strip showing an audit of one of the destination devices.

Figs. 21 and 22 are full sized views of 60 tickets issued by the machine. Fig. 21 is a front view and Fig. 22 a rear view.

Figs. 23^A and 23^B combined constitute a 65 full sized front view of the printing and totalizing mechanism.

Fig. 24 is a detail vertical sectional view 70 taken through a portion of the chute through which the ticket strip is fed.

Figs. 25^A and 25^B combined constitute a 75 detail sectional view through the printing and totalizing mechanisms, the section being taken on the line 25—25 of Figs. 23^A and 23^B.

Fig. 26 is a full sized side view showing 80 two gears through which part of the ticket feeding mechanism is operated.

Fig. 27 is a full sized top plan view of 85 the gears shown in Fig. 26 and shows the gears out of engagement.

Fig. 28 is a full sized detail side view of 90 65 the means for adjusting the printing platen.

Figs. 29^A and 29^B combined constitute a full sized detail sectional view through the printing and totalizing mechanisms, the section being taken on the line 29—29 of Figs. 23^A and 23^B.

Fig. 30 is a full sized detail top plan view 70 of part of the mechanism for operating the means which feeds the tickets out of the machine.

Fig. 31 is a full sized detail sectional view 75 taken on the line 31—31 of Fig. 30.

Fig. 32 is a full sized detail side view of 80 the mechanism for operating the means for feeding the tickets out of the machine and also of the mechanism for operating the device for moving the ticket after it is severed to said feeding means.

Fig. 33 is a full sized detail top plan view 85 of the shaft and the cams thereon for operating the ticket strip and detail strip feeding devices and for rocking the platen frame.

Fig. 34 is a full sized detail side view of 90 part of the platen frame and the cam for operating the frame when the machine is used to make an audit on the detail strip.

Fig. 35 is a full sized side view of the cam and lever for operating the mechanism shown in Figs. 30 and 32.

Fig. 36 is a full sized side view of the 95 cam and lever for operating the means for moving the tickets to the feeding means which feeds the tickets out of the machine.

Fig. 37 is a full sized detail sectional view taken through the cams shown in Fig. 29^B.

Fig. 38 is a detail front view of the operating mechanism of the machine.

Fig. 39 is a detail right hand side view 100 of the operating mechanism of the machine.

Fig. 40 is a detail front view of the means 105 for retaining the operated foot pedal in operated position and preventing a second intermediate operation of the machine by retaining a foot pedal in depressed position at the end of an operation.

Fig. 41 is a full sized detail sectional view taken on the line 41—41 of Fig. 11 but omitting the destination devices.

As above stated, but one destination device for each station is provided in the present invention. Each destination device is adapted to control the issuing of a ticket of any desired class to its appropriate destination station. In the illustrative form of embodiment each destination device is provided with six printing plates or electros, 115 one for each class of tickets, and each plate is adapted to print the name of the destination station and the class of the ticket on a ticket severed from a ticket strip. The six classes represented by the plates of each destination device are "full fare round trip,"

"full fare one way," "half fare round trip," "half fare one way," "excursion" and "clergyman." While the machine is shown 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

as providing for these six classes of tickets it will be obvious that the construction is capable of development to provide a still wider scope without departing from the scope of the invention. Each destination device is also provided with six rows of pinions; one row for each class of tickets. Several of these pinions of each row constitute a consecutive counter which controls type carriers to print on the tickets the number of the tickets of the appropriate class issued to the destination station. One is added on a consecutive counter of the selected destination device during an operation in which a ticket of that particular class is issued. The remaining pinions of a row normally have positions representing the value of the ticket of the particular class and control type carriers for printing the value on the ticket.

The destination devices are carried in an endless chain which is operated by hand wheels, preliminarily to the operation of the machine, to adjust the desired destination device into position to be moved into the printing mechanism. Six foot levers or pedals, one for each class of tickets, are provided with connections to slides which are adopted to move the selected destination device into printing mechanism. The foot levers are constructed to operate the slides to different extents so that when a lever is operated the desired printing plate for printing on the ticket is moved into printing position, the corresponding row of pinions at the same time being moved into position to control the consecutive number and amount type carriers. Operation of a foot lever also releases the operating mechanism of the machine.

During operation of the machine the selected printing plate and the amount and consecutive number type carriers print on a detail strip retained in the machine and also on a ticket severed from a ticket strip. The ticket is then fed out of the machine. An electro prints the name of the issuing railroad as well as the name of the issuing station upon every ticket and a consecutive numbering device prints the number of tickets issued by the machine upon the back of each ticket during the operation in which it is issued. The pinions constituting the consecutive counter first control movement of the consecutive number type carriers, then one is added on the type carriers by suitable mechanism before the consecutive number and the amount are printed on the detail strip and ticket. The amount type carriers are controlled by the pinions representing the amount. After the amount and the consecutive number of the tickets of the particular class are printed the consecutive number and amount type carriers are re-65 stored to zero position whereupon the

amount pinions are set to their original positions and the consecutive numbering pinions are set to represent the consecutive number printed on the ticket and detail strip.

The amount type carriers are provided with actuating segments which through suitable gears actuate a totalizer employed to accumulate the total value of all the tickets issued by the machine.

During the operation of the machine the selected destination device is locked in its adjusted position and near the end of the operation it is released whereupon it is withdrawn from the printing mechanism into normal position in the chain carrying the destination devices.

The printing mechanism is constructed to make a statement or audit upon the detail strip, as for example, when the ticket office at which the machine is located is being checked up by the auditor. In taking an audit the machine is operated a sufficient number of times to print on the detail strip from each printing plate of each destination device, the destination devices being selected and moved into printing position in the same manner as when tickets are to be issued. During such operations the consecutive number type carriers and amount type carriers are controlled by the appropriate pinions in the destination devices and these type carriers and the printing plates print upon the detail strip. The means for adding one on the consecutive number type carriers and pinions is disabled as an incident to preparing the machine for auditing. The ticket strip feeding mechanism is also disabled during such operations so that a printing impression is taken only upon the detail strip during each operation.

Destination devices.

A destination device is shown in detail in Figs. 11 and 13. The casing or frame of each destination device comprises a plate 60, which is bent so as to form a top 63 and sides 64. The top is bent back upon itself along the edges of the sides 64 are bent to form flanges 66 which are parallel to the flanges 65. Six printing plates or electros 67 are mounted on the top 63. The plates 67 are slid in place on the top 63, the latter being provided with projections 68 (Fig. 12) which are cut out of the top and engage over the beveled edges of the plates. Each plate is provided with a notch 69 (Fig. 12) in which engages a vertical projection 70 of a cut-out portion 73 of the top of the destination device to prevent movement of the plate on the device. When a plate 67 is placed on the destination device the cut out portion 73, which acts like a leaf spring, is depressed and then when the notch 69 is in alignment with the projection 70 the por-

tion springs to normal position, moving the projection 70 into the notch 69. Each of these plates is adapted to print the name of the destination station to which the device is appropriate as well as the class of ticket.

5 A plate 74 (Figs. 12, 13 and 14) carrying a card 75, bearing the name of a destination station, is mounted on the forward end of the destination device. The plate 74 has 10 bent projections 76 (Fig. 12) engaging over projection 77 formed on the sides 64 of the destination device, the plate 74 in this manner being mounted on the device.

15 *Means carrying destination devices.*

As shown in Figs. 6^A, 7^A and 11 the destination devices are carried in an endless chain. The chain comprises a plurality of links 94, there being one link for each destination device. Each link comprises a base 95 having bent sides or projections 96 by which the links are connected together. Only a few of the destination devices are shown in Figs. 6^A and 7^A and the bases 95 of 20 most of the links are broken away in these figures as well as in Figs. 6^B and 7^B. The projections 96 of the links overlap as best shown in Fig. 41. Mounted in each projection 96 is a collar or hub 97 fastened to the 25 projection by pins 92. Loose in each collar 97 is a pin or rod 98 upon which is fast a collar 99 which projects through and is rigidly connected by pins 100 to the projection 96 of the next link. Mounted on the collar 30 99 and vertical projections 103 integral with the base 95 of each link is a track 104 having flanges 106. When a destination device is in a link its upper flanges 65 engage over the upper flanges 106 of the tracks 104 and 35 the lower flanges 66 of the destination device engage under the lower flanges 106 of the tracks 104, the destination device in this manner being slidably mounted within the link.

40 Loose on each collar 97 is a roller 108 (Figs. 11 and 41). These rollers 108 are adapted to engage between the teeth of sprocket wheels 109, 110 and 111 (Figs. 2, 6^A-6^B, 7^A-7^B and 8). The chain passes over 45 the pair of sprocket wheels 109 at the top of the machine and under the pair of sprocket wheels 111 near the bottom of the machine. The pair of sprocket wheels 110 intermediate the sprocket wheels 109 and 50 111 do not support the chain, the function of these sprocket wheels being to move the chain as will be described later. The pair of sprocket wheels 111 are fast on a shaft 113 mounted in brackets 114 (Figs. 2 and 55 6^B) fast on the base 115 of the machine. Mounted in the base 115 are four vertical rods 116. Two vertical frames 117 (Figs. 6^A-6^B and 8) mounted on the rods 116 support a shaft 118 upon which is fast the pair 60 65 of sprocket wheels 110. Crossbars 119 (Figs.

6^A and 7^A) mounted upon the upper ends of the rods 116 support a shaft 120 upon which is fast the pair of sprocket wheels 109.

The vertical portions of a guide track 123 (Figs. 2, 6^A-6^B, 7^A-7^B, 8, 9, 10, 21 and 23) 70 are fast to horizontal frames 124, 125, 126 and 127 mounted on the rods 116. The upper semi-circular portion of the track 123 is supported by a frame 128 (Fig. 7^A) loose on the shaft 120 and the lower semi-circular 75 portion of the track 123 is fast on a frame 130 (Figs. 2 and 7^B) loose on the shaft 113. The track 123 is also fast on a frame 131 (Figs. 7^A, 8, 21 and 23) supported on the shaft 118 and a shaft 132 journaled in the 80 frames 117. This guide track comprises a strip or band 134 upon which is fast an angular strip or band 135 which is bent to form two guideways 136 between the bands 134 and 135. The sides 64 (Figs. 11 and 85 12) of the destination devices carry rollers 137 near their rear ends and these rollers, as best shown in Figs. 7^A and 8, are adapted to move in the guide-ways 136. From this construction so far described, it can be seen 90 that when the chain carrying the destination device is moved the engagement of the rollers 137 in the guide-ways 136 prevents the destination devices from sliding out of the links of the chain.

95 Means are provided to permit a destination device to be readily inserted or removed from the chain, as for example, when a destination device needs repair or is to be changed in some manner. To this end a small block 143 (Figs. 4, 5, 6^A and 7^A) is provided with grooves 144 in its sides, the grooves being in alignment with the guide-ways 136 of the track 123 when the block is in position, as shown in the drawings. The 100 block 143 is mounted on a vertical projection 145 of the frame 126 by means of a thumb screw 146. When a destination device is to be removed the screw 146 is turned to permit removal of the block 143 and then the 110 chain is adjusted to bring the rollers 137 of the destination device in the open space in the track caused by the removal of the block so that the destination device may be slid out of the link 94 in which it is mounted. 115 The operator may have access to the screw 146 to remove or insert a destination device, through a door 149 in the back of the cabinet of the machine.

120 Fast on the shaft 118 (Figs. 6^A and 8) is a gear 150 meshing with a gear 153 fast on the shaft 132. Hand wheels 155 fast on ends of the shaft 132 are adjusted by the operator to rotate the pair of sprockets 110 through the gears 150 and 153 and thereby adjust the 125 chain to move the desired destination device into position to be moved into printing position. When a destination device is in position to be moved into the printing mechanism its rollers 137 are in small movable 130

tracks 156 (Figs. 7^a, 14 and 17) normally positioned in an open space in the track 123. These movable tracks 156 will be described more specifically later. The front of the 5 machine is provided with a window 158 (Figs. 1 and 7^a) through which the names of the destination stations on the front ends of the destination devices may be viewed by the operator. It is obvious that the 10 names of the destination stations on the destination devices are not appropriate to the stations represented by the devices carrying them but that the name on each destination device, when the device is moved opposite an arrow 159 (Fig. 1) adjacent the window 158 is appropriate to the destination device in position to be moved into the printing mechanism, this arrangement of the names on the destination devices being employed 15 so as to enable the operator to move the desired destination device into position to be moved into the printing mechanism. The names on a number of destination devices are displayed at the same time through 20 the window 158 so that the operator, who, of course, is familiar with the routes, can readily determine which way to adjust the hand wheels 155 to move the desired destination device the shortest distance into position to 25 be moved into the printing mechanism.

In order to guide the chain carrying the destination devices and retain the rollers 108 on the chain in engagement with the sprocket wheels 110 four vertical tracks 160 (Figs. 2, 35 6^a—6^b, 8, 9 and 10) are mounted on the frames 117, 119, 124, 125, 126, 127 and frames 161 (Figs. 2 and 6^b) loose on the shaft 113. Each track comprises a strip 163, and an angular bar or strip 164 which form 40 guide-ways in which the rollers 108 move so as to guide the chain and prevent disengagement of the rollers 108 from the sprocket wheels 110.

45 *Means for moving selected destination device into printing position.*

After the selected destination device has been adjusted into position to be moved into the printing mechanism, as above described, 50 the destination device is moved by the following described means into the printing mechanism so that the desired printing plate 67 is in position to print on the ticket to be issued.

55 The small tracks 156 (Figs. 14, 16 and 17), in which the rollers 137 of the selected destination device engage, are fast on the forward end of a slide 167 provided with a slot 168 through which pins 169 on a slide 170 60 project. The slide 170 carries pins 173 which project through a slot formed in a bar 174 fast on the frame 131. The slot in the bar 174 coincides with the slot 168 in Fig. 14. The slide 167 near its rear end carries pin 176 (Fig. 14) projecting through a

slot 181 formed in the upper end of an arm 177 pivoted on a cross rod 178 (Figs. 6^b and 7^b) mounted in brackets on the frame 125. Pivoted on the cross rod 178 and fast to the arm 177 is an arm 179 (Figs. 6^b, 7^b and 9) 70 carrying a rod 180. The rod 180 carries rollers which project through V-shaped slots 183 formed in the upper ends of six levers 184 pivoted on the shaft 113 (Figs. 2, 6^b and 7^b). Rigidly mounted on the lower end 75 of each lever 184 is a foot pedal 185 projecting through slots 186 (Figs. 1 and 3) in the base 115 of the machine. Springs 182 interposed between rearwardly extending arms 187 of the lever 184 and a cross rod 188 serve 80 to retain the levers 184 in the normal position shown in Figs. 6^b and 7^b. The rearwardly extending portions 189 of the slots 183 are differentially inclined. From the above description it can be seen that when 85 the foot pedal 185 is depressed the corresponding lever 184 is rocked clockwise whereupon the portion 189 of the slot 183 in the lever raises the rod 180 thereby rocking the arms 177 and 179 clockwise. As the 90 portions 189 of the slots are differentially inclined it is obvious that the lever 177 is rocked clockwise to an extent dependent upon the foot pedal depressed. For example if the "full fare one way" foot pedal is de- 95 pressed the lever 177 is rocked one step; if the "full fare round trip" foot pedal is operated the lever 177 is rocked two steps and so on, the lever 177 being rocked six steps when the "clergyman" foot pedal is operated. When the lever 177 is rocked in this manner it can be seen that the slides 167 and 170 (Figs. 21, 23 and 24) are moved forwardly, the extent of movement of the slides being dependent upon the movement of the 105 lever. As the rollers 137 on the selected destination device engage in the track 156 movement of the slide 167 moves the selected destination device forwardly out of the corresponding link 94 of the chain and into the 110 printing mechanism to an extent dependent upon the foot pedal operated.

The portions 193 (Figs. 6^b and 7^b) of the slots 183 are concentric with the cross rod 178 and coincide when the levers 184 are in normal position. Therefore when one of the levers 184 is operated the rod 184 is moved into the portions 193 of the slots of the levers which are not operated thereby preventing operation of one of the latter after opera- 115 tion of the desired lever is begun.

It is desirable to lock the chain carrying the destination devices against adjustment during operation of a foot pedal 185 and operation of the machine to insure movement of the selected destination device to its normal position in the chain when the foot pedal is restored to normal position near the end of the operation of the machine. It might be well to state here that the oper- 120 125 130

ated foot pedal 185 is held in operated position during operation of the operating mechanism which will be described later. The operated foot pedal 185 at such time is moved to normal position by the corresponding spring 182 and, of course, upon such movement of the foot pedal the selected destination device is moved back into its link 94 in the chain. The means for locking the chain against movement will now be described. Loose on the cross rod 178 (Figs. 6^B, 7^B and 9) is a frame comprising two arms 195 and two cross bars 192 and 196. A rod 197 is mounted in the cross bar 196. Rollers 191 on the rod 197 engage inclined edges 198 on the levers 184. Two links 199 are pivoted at their lower ends on the rod 197 and near their upper ends are provided with slots 200 through which projects a cross rod 203 mounted in the frames 117. The inclined edges 198 of the levers 184 are so constructed that when a lever is rocked clockwise, as above described, the links 199 are raised to move projections 204 on the upper ends of the links between teeth on the corresponding sprocket wheels 110 thereby locking the sprocket wheels and chain against adjustment. The links 199 are elevated during the initial movement of the operated lever 184 and are retained in elevated position by engagement of one of the rollers 191 on the upper curved edge 205 of the lever 184 during operation of the machine. When the operated lever 184 is rocked back to normal position near the end of the operation of the machine a spring 206 (Fig. 6^B) lowers the links 199 to move their projections 204 out of engagement with the sprocket wheels 110 to permit adjustment of the chain preliminary to the next operation of the machine. It is obvious that engagement of the projections 204 on the links 199 with the sprocket wheels 110 also alines the chain in its adjusted position.

After a destination device has been moved differentially into printing position it is alined in its adjusted position during operation of the machine by the following described means. An arm 207 (Figs. 7^A, 14 and 18) is pivoted on the frame 131 and projects through an opening in the track 123, as shown in Fig. 18. A link 208 is connected to the arm 207 and to an arm 209 (Figs. 6^B, 7^B and 9) loose on the cross rod 178. Rollers 210 mounted on a rod 213 connecting the link 208 to the arm 209 rest upon the curved edges 205 of the levers 184. Near the end of a clockwise movement of the operated lever 184 a cam projection 214 on its upper edge engages one of the rollers on the rod 213, thereby rocking the arm 209 and raising the link 208 against the action of a spring 215 interposed between the arm 209 of the frame 124. When the link 208 is raised in this manner the arm 207 is rocked counter clockwise (Fig. 14) whereupon its nose 216 engages in one of the V-shaped notches 217 cut in the lower edge of the slide 167 to lock and aline the slide and the selected destination device in adjusted position. When the link 208 is raised the destination device is already in adjusted position, the rear ends of the portions 189 of the slots 183 in the levers 184 being concentric with the shaft 113 so that while the link 208 is being raised the destination device is not being moved. As the operated foot pedal is not restored to normal position until near the very end of the operation of the machine it can be seen that the selected destination device is locked in adjusted position during operation of the printing mechanism and is released during the initial return movement of the operated foot pedal to normal position, the spring 215 serving to move the locking arm out of locking position when the cam projection 214 on the lever 184 is moved out of engagement with one of the rollers on the rod 213.

In order to prevent simultaneous depression of two or more foot pedals a well known form of locking devices 220 (Fig. 3) is provided. These devices are in the form of arms pivoted at 223 on the base 115 of the machine. When a foot pedal is depressed it separates and moves between two of the arms, movement of which is limited by projections 224 projecting into recesses 225 in the upper ends of the arms so that but one foot lever can move between two arms at a time, as is well known in the art whereby two foot pedals can not be operated at the same time.

When a destination device is moved out of a link in the chain into the printing mechanism it slides off of the tracks 104 in the link onto tracks 226 (Figs. 25^B, 29^B and 41), which at such time are in alinement with the tracks 104. The tracks 226 are formed on bars or frames 227 mounted on three cross rods 228. The cross rods 228 are mounted in the sides of a frame 229 fast on the two front rods 116. The upper flanges 65 of the destination device slide on the top edges of the tracks 226 and the lower flanges 66 of the destination device engage under the lower edges of the tracks 226.

When a destination device has been moved into the printing mechanism its selected printing plate 67 is under a printing platen 230 (Figs. 25^B and 29^B) adapted to carry the ticket against the plate.

When the amount type carriers and consecutive number type carriers are positioned in a manner outlined in the parent application the type representing the amount and the type representing the consecutive number are on the printing line, in alinement with the selected printing plate 67. While in this position impressions are taken from the

type carriers and the printing plate 67 onto the ticket and a detail strip, which will be described later.

5 *Ticket printing and feeding means.*

The ticket strip 332 is fed from a supply roll 335 (Fig. 6^A) through a chute 337 in alinement with the chute 336 (Figs. 25^A-25^B). The end of the ticket strip is normally in engagement with a movable knife 338. Near the beginning of the operation of the machine the ticket strip is fed the length of one ticket by a printing and feeding cylinder 339 and an impression roll 340 to move the end portion of the strip, which is to constitute the ticket, under the printing platen 230. While the end portion of the ticket strip is under the platen 230 it rests on a table 343 which is pivoted on a cross rod 344 supported in frames 345 (Figs. 23^A-23^B, 25^A-25^B and 32). The frames 345 are pivoted on a cross rod 346 mounted in the sides of the frame 229. The chute 337 is fast on a frame 347 (Figs. 25^B and 29^B) mounted on the frames 345. The frame 347 has a slot 341 (Fig. 25^B) through which the ticket strip is fed. The ends of the cylinder 339 are fast on the ends of shafts 348 (Figs. 25^A and 29^A) which are in alinement and journaled in the frames 345. The shafts 348 and cylinder 339 are rotated in the direction of the arrow (Fig. 25^A) in a manner to be described later and during such rotation feeding flanges on the cylinder coöperate with an impression roll 340 to feed the ticket strip the length of the ticket near the beginning of the operation of the machine.

The platen 230 (Fig. 25^B) is loose on a cross rod 349 mounted in frames 350 (Figs. 25^A-25^B and 29^A-29^B) pivoted on the cross rod 344. The frames 350 are connected by cross rods 353. The ends of the cross rod 349 (Fig. 28) project through slots in the frames 350 and are mounted in plates 355 which together with the cross rod and platen are adjustable relative to the frames 350 by means of slot and screw connections 356 in a manner well known in the art so that impressions of the desired distinctness may be made on the ticket and detail strip. Projections 357 on the frames 350 (Figs. 25^B and 29^B) project into recesses (not shown) formed in the movable knife 338. Pins 358 (Fig. 25^B) mounted in the frame 347 project through vertical slots (not shown) in the knife 338 to permit the knife to be raised and lowered. A block 359 is fast on the forward ends of the pins 358. Compressed springs 360 coiled about the pins 358 serve yieldingly to retain the block against the movable knife and the knife against the frame 347.

The right hand frame 350 (Fig. 25^A) carries a roller 363 projecting into cam groove 364 formed in the face of a disk 365 fast

on a shaft 366 which is mounted in the frames 345 and given one complete rotation in the direction of the arrow upon each operation of the machine by the operating mechanism to be described later. The cam groove 364 is so constructed that the frames 350 are first rocked counter clockwise (Figs. 25^A-25^B) to raise the platen 230 and the movable knife 338 for the purpose of permitting the end of the ticket strip to be fed on to the 70 table 343 and under the platen. Then after the type carriers have been adjusted to represent the amount and the consecutive number of the ticket the frames 350 are rocked clockwise past normal position by the cam 75 groove 364. During this movement of the frames the knife 338 first severs the ticket and then the platen 230 moves the ticket against the selected printing plate 67 and the amount and the consecutive number type 80 carriers to take printing impressions therefrom (Fig. 21). It is obvious that when the platen 230 is lowered to carry the ticket against the type carriers and the printing plate 67 the table 343 (Figs. 25^B and 29^B) 85 is rocked by the platen against the action of springs 361 which serve to hold this table in normal position. The cam groove 364 then rocks the frames 350 counter clockwise to normal position and while in this position the ticket is fed by the following described means to a feeding and printing cylinder 373 and an impression roll 370 90 which feed the ticket out of the machine.

Fast on a shaft 375 supported in the 100 frames 350 is a frame 376 comprising two side arms 377 (Figs. 25^A-25^B and 29^A-29^B) and a cross bar 378. The cross bar 378 is provided with ridges 379 the sharp edges of which are adapted to bite into the ticket. 105 The frame 376 carries a roller 380 (Figs. 25^A and 32) projecting into a slot formed in a lever 383 pivoted on a stud 384 projecting from the right hand frame 345. The lever 383 carries a roller projecting into a 110 cam groove 390 formed in the left hand face of a disk 393 splined on the shaft 366 by a spline 394. The cam groove 390 is so constructed that after a ticket has been severed from the ticket strip and printed upon by 115 the printing plate 67 and type carriers the frame 376 (Figs. 25^A-25^B) is rocked counter clockwise whereupon its ridges 379 engage the ticket and move it on the table 343 to the feeding cylinder 373 and impression 120 roll 370. The frame 376 is then rocked to normal position, the ticket at such time being held by the impression roll 370 and cylinder 373 against return movement with the frame 376.

The right hand end of the cylinder 373 is fast on a shaft 397 (Figs. 23^B, 25^B, 30 and 32) journaled in the right hand frame 345. A tube 401 (Figs. 23^B and 29^B) fast to the left hand end of the cylinder is journaled 130

- in the left hand frame 345. Loose on the shaft 397 is a gear 398 (Figs. 30 and 32) meshing with a gear 399 fast on a shaft 400 upon which is fast the impression roll 370. 5 Fast to the gear 398, but loose on the shaft 397, is an arm 403 carrying a pawl 404 which is retained by a spring in engagement with a ratchet wheel 405 fast on the shaft 397. Fast on the shaft 400 is a gear 406 meshing 10 with a segmental rack portion on a lever 407 pivoted on the stud 384. The lever 407 carries a roller projecting into a cam groove 409 (Fig. 35) formed in the right hand face of the disk 393. This cam groove 409 15 is so constructed that the lever 407 is rocked counter clockwise (Fig. 32) and then rocked clockwise to normal position. The clockwise movement begins at the time that the ticket is fed to the roll 370 and cylinder 373 20 by the frame 376, as above described. Movement of the lever 407 rotates the roll 370 one complete rotation, first in a clockwise direction (Fig. 25^B) and then in a counter clockwise direction to normal position. It is obvious 25 that through the gears 398 and 399, the arm 403 is rotated one complete rotation, first counter clockwise (Fig. 32) and then clockwise to normal position. During counter clockwise movement of the arm 403 30 the pawl 404 rides idly on the ratchet wheel 405 and upon clockwise movement the pawl 404 rotates the ratchet wheel and therefore the cylinder 373. During counter clockwise rotation of the roll 370 and clockwise rotation of the cylinder 373 the roll and cylinder coöperate to feed the ticket through a chute 410 and out of the machine. A spring 35 operated retaining lever 413 (Figs. 30 and 31) pivoted on a cross rod 411 mounted in the frames 345 coöperates with a ratchet 414 40 fast on the shaft 397 to prevent counter clockwise rotation of the cylinder 373 during counter clockwise rotation of the arm 403. 45 In order to prevent the roll 370 and cylinder 373 from being rotated past normal position when they eject the ticket the following device is employed. Fast on the shaft 397 is a disk 415 (Figs. 30 and 31) 50 provided with stop projection 416 which normally engages the end of an arm 417 (Fig. 32) pivoted on the shaft 400. A spring 418 serves to retain the arm 417 in normal position. Near the end of the clockwise rotation of the gear 399 a pin 419 on the gear engages the arm 417 to rock it to the position shown in Fig. 31 in which position the initial counter clockwise movement of the gear 399 the stop projection 416 is 55 moved over the arm 417 so that when the pin 419 moves out of engagement with the arm 417 the latter engages the end of the stop projection 416 thereby permitting rotation of the cylinder 373. During rotation 60 of the cylinder 373 the end of the arm 417 65 rides on the periphery of the disk 415 and is engaged by the stop projection 416 at the end of the rotation of the cylinder to prevent overthrow of the latter. A consecutive counter 420 (Fig. 25^A) 70 mounted within the cylinder 339 and operated by a pawl 423 in a manner well known in the art is employed to print the consecutive number of the tickets issued by the machine on the backs of the tickets as shown 75 in Fig. 22. An electroplate mounted on the cylinder 339 may be employed to print any desired directions or information on the backs of the tickets. An inking roll 421 mounted on a cross rod 422 supported in the 80 frames 345 inks the electroplate and the type wheels of the consecutive numbering device 420 during rotation of the cylinder. 85 The printing and feeding cylinder 373 (Fig. 25^B) is provided with an electroplate 90 adapted to print the name of the railroad and the name of the issuing station on the face of the ticket as shown in Fig. 21. Date wheels 425 (Fig. 29^B) in the cylinder 373 are fast on sleeves 426 and a shaft 432 adjusted in the usual manner by turn knobs 427 (Figs. 1 and 23^B). These date wheels also print the date upon the face of the ticket (Fig. 21) as the roll 370 and cylinder 373 feed the ticket out of the machine. An ink 95 roll 431 (Figs. 25^B and 29^B) on the cross rod 411 inks the date wheels and electroplate during rotation of the cylinder 373. 100 An endless inking ribbon 430 (Figs. 23^A, 25^A, 25^B, 29^A-29^B and 32) through which the printing impressions are made from the selected plate 67 and type carriers on the detail strip and ticket, passes over two rollers 433 mounted on a cross bar 434 fast on the frames 345 and passes under two rollers 105 436 mounted on the frame 347. This inking ribbon, which may be fed by any desired means, passes under the platen 230 and through slots formed in the sides of the table 343, as shown in Fig. 25^B. 110 As before stated, the frames 345 (Figs. 25^A and 25^B) are pivoted on the cross rod 346. A shaft 438 (Figs. 23^B, 24 and 25^A) is mounted in frames 349 fast on the front rods 116. The shaft 438 passes through circular recesses in the frames 345. This shaft is cut away at 441 and these cutaway portions are in the same planes as the frames 345. The shaft 438 may be turned by a knob 442 (Fig. 23^B) to move its cut-away portions into such position that the frames 345 115 may be rocked forwardly about the cross rod 346. The shaft 438 is constructed to permit rocking of the frames 345 so that in case the ticket strip should buckle between the cylinder 339 and the impression roll 340 the buckled portion may be torn off to permit proper feeding of the strip. Access may also be had more readily to the various parts carried by the frames 345. The chute 120 125 130

336 is slidably mounted on a vertical portion 440 (Figs. 24 and 25^A) of the cabinet, the chute being provided with pins 443 which project through slots 444 (Fig. 23^A) 5 formed in the portion 440 of the cabinet. The lower end of the chute projects into a member 445 (Fig. 25^A) which is fast on the end of the chute 337 and serves to retain the chutes 336 and 337 in alinement. Before the frames 345 are rocked, as above described, the chute 336 is manually raised to move it out of the member 445 and thereby 10 permit movement of the frames 345. The shaft 366 is cut away at 451 to permit the end of the chute 336 to be raised above the shaft.

Detail strip.

The detail strip 450 (Figs. 23^A, 25^A-25^B 20 and 29^A-29^B) is fed from a supply roll 453 thence under a roller 454, over a roller 455, under the platen 230, past a guide roller 456, over a roller 457, under a roller 458, over a roller 459 onto a storage roller 460. The 25 rollers 455 and 456 are mounted on the cross rods 353. The rollers 458 and 459 are loose on cross rods mounted in the frame 345. The rollers 454 and 457 are mounted on cross rods carried by levers 463 fast on 30 a shaft 464 journaled in the frames 345. Fast on the shaft 464 is an arm 465 (Fig. 29^A) carrying a roller projecting into a slot 466 formed in the left hand frame 350. The cam groove 364 (Fig. 25^A) in the disk 365 35 is so constructed that after the frames 350 have been rocked to carry the ticket against the printing plate 67 and the type carriers as above described, these frames are rocked counter clockwise and then rocked clockwise 40 so that the platen 230 carries the detail strip against the printing platen and type carriers to make an impression thereon. The detail strip is carried against the print plate 67 and type carriers after the ticket 45 has been moved from under the platen by the feeding frame 376. The levers 463 are normally in the positions shown in Figs. 25^A and 29^A to hold the detail strip firmly against the platen. When the frames 350 50 are rocked clockwise to take impressions on the ticket and the detail strip the slot 466 (Fig. 29^A) rocks the arm 465, shaft 464 and arms 463 clockwise to permit lowering of the platen without feeding the detail strip 55 from the supply roll, the levers being moved back to normal position when the frames 350 are rocked counter clockwise.

After the detail strip has been printed upon it is fed one step on the storage roll 460 by the following described mechanism. The storage roll 460 and supply roll 453 (Fig. 29^A) respectively are loose on rods 461 and 462 projecting from the left hand frame 345. Pivoted on the rod 461 is a lever 65 468 carrying a pawl 469 which is retained

by a spring in engagement with a ratchet wheel 470 fast on the storage roll 460. A pin 473 on the lever 468 projects through a recess in a lever 474 pivoted on a stud 475 projecting from the left hand frame 70 345. The lever 474 carries a roller projecting into a cam groove 476 formed in the face of a disk 477 splined on the shaft 366 by a spline 478. The cam groove 476 is so constructed that a printing impression has been 75 taken on the detail strip the lever 468 is rocked counter clockwise through the lever 476 whereupon the pawl 469 rotates the ratchet wheel 470 and the storage roll 460 one step to feed the detail strip on the latter. A spring operated pawl 479 engages the ratchet wheel 470 to prevent retrograde movement of the storage roll.

Operating mechanism.

85

The form of clutch and motor connections shown in Figs. 38 and 39 has become well known in the art and is fully shown and described in Letters Patent of United States No. 1,144,418 granted to Chas F. Kettering and Wm. A. Chryst, June 29, 1915, 90 and therefore will not be described in detail here.

In general the clutch comprises a disk 555 (Figs. 38 and 39) which is adapted to be 95 given a slight preliminary movement under the action of a spring (not shown) to couple two clutch members 556 and 557 together by means of rollers 561. The clutch member 557 is fast to a gear 558 meshing with a worm gear 562 driven positively by the motor (not shown). The disk 555 is normally restrained from such preliminary movement by engagement of a block 559 (Fig. 39) on the disk with the nose of a 100 locking lever 560 which is pivoted on a stud 563 projecting from the frame 229. When the lever 560 is rocked counter clockwise (Fig. 38) to move the nose of the lever out of engagement with the block 559, as 105 will be presently described, the disk 555 is moved to couple the two clutch members together by the rollers 561. At the same time the nose of the lever 560 is moved out of engagement with the shoulders on two 110 disks 564 which close the motor circuit as described in the aforesaid patent. The clutch member 556 is fast on a shaft 565 carrying a gear 566 (Fig. 38) meshing with a gear 567 fast on a vertical shaft 568 which 115 is journaled in brackets on the frame 229. Fast on the shaft 568 is a bevel gear 569 (Fig. 39) meshing with a bevel gear 570 fast on a stub shaft 573 journaled in the frame 229. Also fast on the shaft 573 is a 120 gear 574 (Fig. 32) meshing with a gear 575, fast on the shaft 366. The gear 575 in turn meshes with a gear 576 fast on the right hand shaft 348 carrying the printing and feeding cylinder 339. Through these con- 125 130

nections it can be seen that the motor is adapted to give the shafts 366 and 348 one complete rotation in the direction of the arrows during each operation of the machine. Also fast on the shaft 568 (Fig. 39) is a bevel gear 577 meshing with a bevel gear 578 fast on a shaft 579 journaled in brackets 580 fast on the frame 229. Also fast on the shaft 579 is a bevel gear 583 meshing with a bevel gear 584 splined on the cam shaft 245. Through these connections the cam shaft 245 is given one complete rotation in the direction of the arrows (Figs. 25^b, 29^b and 39) upon each operation of the machine.

If desired a crank handle 581 (Fig. 38) may be employed to operate the machine. The crank handle 581 is fast upon the shaft 573 so that upon each complete rotation of the crank handle the shafts 245 and 366 are given one complete rotation through the above described gear connections between the shaft 573 and the shafts 245 and 366.

The means for operating the locking lever 560 to release the machine will now be described. Loose on a cross rod 586 (Figs. 6^b, 7^b and 10) mounted in the frame 124 is a lever 587, the rear end of which carries a rod 588 upon which is mounted rollers 589 projecting through slots 590, which are formed in the levers 184. The forward end of the lever 587 is pivoted to the lower end of a link 594, which at its upper end is pivoted to an arm 595 (Fig. 38) pivoted at its left hand end on the frame 229. Pivoted to the right hand end of the arm 595 is a link 596 which carries a stud 597 normally engaging a notch 598 formed in an arm 599 which is pivoted on the frame 229. A spring 600 (Fig. 38) interposed between the link 596 and an arm of the locking lever 560 normally retains the stud 597 in the notch 598 and the lever 560 in locking position. One arm of the lever 560 carries a roller 603 projecting into a notch formed in the arm 599. Mounted on the stud 568 and a shaft 604 is a plate 605 having a notch 606. The shaft 604 is mounted in the frame 229 and the front bracket 580. Projecting from a disk 607, fast on the shaft 579, is a pin 608 (Fig. 40) adapted to engage an edge 609 on the upper end of the link 596. The slots 590 (Figs. 6^b and 7^b) in the levers 184 are all the same and are so constructed that when one of the levers is operated the corresponding slot rocks the lever 587 clockwise near the very end of the clockwise movement of the lever, the rod 588 at such time being raised by the rear cam portion 610 of the slot. When the rod 588 is raised by one of the levers 184 it moves into the forward portions 613 of the slots in the other levers, these portions being concentric with the cross rod 586. Clockwise movement of the lever 587 lowers the link 596 to

the position shown in Fig. 40. As the stud 597 on the link 596 engages in the notch 598 in the arm 599 the locking lever 560 is rocked counter clockwise to effect release of the motor as above described.

When the link 596 is lowered to the position shown in Fig. 40 its stud 597 engages in the notch 606 of the arm 605, the arm thereby serving to retain positively the link in moved position. The rod 588 (Fig. 7^b) is therefore retained in the portion 610 of the slot 590 in the operated lever 184 to hold the latter in operated position during operation of the machine.

Near the end of the operation of the machine the pin 608 engages the edge 609 (Fig. 40) of the link 596, thereby rocking the link clockwise about its pivot and against the action of the spring 600 to move its stud 597 out of engagement with the notches 598 and 606. At such time the spring 600 rocks the locking lever 560 and the arm 599 to normal position to disconnect the motor clutch and break the motor circuit. When the arm 599 is moved to normal position and the pin 608 moves out of engagement with the edge 609 of the link 596 the spring 600 rocks the link 596 counter clockwise until arrested by engagement of the stud 597 with the arm 599 below the notch 598. From this construction it can be seen that if the operated foot pedal 185 is held in operated position at the end of an operation of the machine a second immediate operation of the machine will not be effected, as the pin 597 does not retain the locking lever in operated position. When the operated foot pedal 185 is finally released its spring 182 restores it to normal position and the link 596 is raised to normal position whereupon the spring 600 rocks the link to move its stud 597 into normal engagement with the notch 598 in the arm 599. When the operated foot pedal 185 is rocked to normal position by its spring 182 it is obvious that the links 199 (Figs. 6^b and 7^b) are lowered by the spring 215, that the arm 195, link 208 and locking arm 207 (Fig. 14) are moved to normal position by the spring 206 (Fig. 6^b) and that the arms 177 and 179, slides 167 and 170 (Figs. 14, 16 and 17) and the selected destination device are moved to normal position by the action of the cam slot 183 (Fig. 7^b) in the operated lever 184.

For the purpose of positively restoring the locking lever 560 to normal position near the end of the operation of the machine one arm of a lever 611 (Figs. 38, 39 and 40) fast on the shaft 604 carries a roller projecting into a cam groove 612 (Fig. 40) formed in a face in the disk 607 and the other arm of the lever 560 is provided with a recess (Fig. 38) through which a pin 602 on an arm of the locking lever 560 projects. The cam groove 612 is constructed so that when the locking lever 560 is rocked to release the machine the

lever 611 is permitted to rock to the position shown in Fig. 40. Near the end of the operation of the machine the lever 611 and locking lever 560 are positively restored to 5 normal positions by the cam groove 612.

- When the shaft 438 (Figs. 23^A and 25^A) is turned and the frames 345 are rocked about the cross rod 346 (Fig. 32) it can be seen that the gear 575 is moved out of mesh 10 with the gear 574. In order to prevent any rotation of the gear 575 and shaft 366 while the gears 574 and 576 are out of mesh a pawl 614 is provided. The pawl is pivoted 15 on a cross rod 615 mounted in the frames 345. A vertical arm 616 of the pawl normally engages a projection 617 on one of the frames 439 to retain the nose of the pawl out of engagement with the gear 575 while the gears 574 and 575 are in mesh. A spring 20 621 is compressed between the arms 616 and a stud 622 on the right hand frame 345. It can be seen from this construction that when the frames 345 are rocked clockwise about the cross rod 346 the spring 621 rocks the 25 pawl 614 counter clockwise to move its nose into engagement with the gear 575 and therefore retain the gear in normal position. When the frames 345 are rocked back to normal position the arm 616 of the pawl engages 30 the projection 617 thereby moving the nose of the pawl out of engagement with the gear 575.

Audit.

- 35 As heretofore stated in the early part of the specification, the machine embodying the present invention is constructed so that an audit of the business may be had at any desired time.
- 40 When an audit of the business is to be made the machine is given a sufficient number of operations to print on the detail strip 450, the name of the destination station and the class of ticket from each printing plate 45 67 of each destination device and to print the consecutive number of the tickets of each class issued to each station and the fare. After the machine is prepared for auditing as will be described presently, the destination devices are preferably moved successively by adjustment of the hand wheels 155 into position to be moved into the printing mechanism as in ticket printing operations. After a destination device has been moved 55 into such position the six foot pedals 185 (Fig. 1) are depressed preferably in succession from left to right before the next destination device is adjusted into position to be moved into the printing mechanism. 60 Therefore, the machine is given six operations to make a complete audit of each destination device and the audits of the various devices are printed in succession on the detail strip. When an audit is made by the
- machine from all of the destination devices 65 the auditor can ascertain the cash value of the tickets of each class sold to each station by multiplying the consecutive number in question by the fare rate. The various products can then be added together and the 70 result compared with the cash on hand and the total accumulated on the totalizer.
- As the totalizer and consecutive number mechanisms are fully covered in the original application they are not shown and described in detail herein.
- When the shaft 366 (Figs. 26, 27 and 32) is shifted toward the right a pin 633 on an arm 634 shifted with the shaft 366 engages between teeth on the gear 576 positively to 80 prevent any rotation of the printing and feeding cylinder 339. The pin 633 is normally out of engagement with the gear 576 to permit rotation of the cylinder 339 during ticket printing operations. The arm 85 634 is loose on the shaft 366 and its hub 636 carries a pin 637 engaging in a groove 638 in the shaft 366 so that the arm 634 is shifted with the shaft 366 and the shaft is rotated independently of the arm. The 90 lower end of the arm 636 is provided with a recess through which the shaft 348 projects to prevent rotation of the arm 634.
- The cam disk 393 (Figs. 33, 35 and 36) for operating the ticket feeding frame 376 95 and ticket feeding roller 370 and cylinder 373 (Figs. 25^A-25^B) as above described, is splined on the shaft 366 by the spline 394. The spline 394 is fastened in a groove 640 in the shaft and is long enough to cause the 100 disk to be rotated with the shaft during both ticket printing and auditing operations. The disk 393 is prevented from moving laterally with the shaft by the rollers on the levers 383 and 407. It is, therefore, 105 obvious that during auditing operations the ticket feeding frame 376 and the roller 370 and cylinder 373 are operated as in ticket printing operations, but as no ticket has been printed and severed from the ticket 110 strip, movements of these parts are idle.
- Fast on the shaft 366 is a disk 644 (Figs. 33 and 34) provided with a cam groove 645. When the shaft 366 is shifted toward the right, to prepare the machine for auditing, 115 the disk 365 (Figs. 25^A and 33) is shifted with the shaft to disengage its cam groove 364 from the roller 363 on the right hand one of the frames 350 which carry the platen 230. At the same time the cam disk 644 is 120 shifted so that a roller 646 (Figs. 33 and 34) on the left hand frame 350 projects into the cam groove 645. This cam groove 645 is so constructed that during an operation in which the machine is used to audit the 125 frames 350 are rocked clockwise (Figs. 25^A and 25^B) but once so that the printing platen 230 carries the detail strip against the se-

lected plate 67 on the selected destination device and against the adjusted amount and consecutive number type carriers.

The disk 477 for operating the detail strip feeding mechanism shown in Fig. 29^A is splined on the shaft 366 by the spline 478 (Figs. 23^A, 29^A and 33). The spline is fastened to the disk 477 and loose in the groove 640 in the shaft 366 so that the shaft may be shifted independently of the disk 477 and so that the disk is rotated with the shaft. The disk 477 is prevented from being shifted toward the right with the shaft 366 by the roller 472 on the lever 474 and is prevented from shifting toward the left with the shaft by engagement of the left hand end of the spline 478 with a bearing 650 fast on the left hand frame 345. Therefore, the detail strip feeding mechanism is operated during each auditing operation in the same manner as during ticket printing operations.

The bevel gear 584 (Figs. 38 and 39) is splined on the shaft 245 and is held against lateral movement by the frame 229 and bracket 580. Therefore, the shaft 245 is shifted independently of the gear 584 and is given one complete rotation by the operating mechanism upon each operation when the machine is used for auditing or issuing tickets.

The shaft 245 may be shifted independently of cams 275, 285 and 329 which drive the differential mechanism for the type carriers, the zero stop arms of the ticket counters and the alining frame respectively, by reason of the constructions shown in Fig. 37. The cams mentioned are splined on the shaft 245 by the spline 272 (Figs. 23^B, 29^B and 37). The spline 272 is loosely mounted in a groove 660 in the shaft 245 so that the shaft may be shifted independently of the spline. The right hand end of the spline has a projection 663 (Fig. 37) engaging the right hand face of the disk 285. The left hand end of the spline is provided with a projection 664 which engages the inside of a circular flange 665 of a hollow cylindrical member 666 fast on the frame 229. A hub 667 on the disk 275 engages the circular flange 665 of the member 666. Hubs of the disks 275 and 329 are in engagement and the hub of the disk 285 is in engagement with the disk 329 to hold the disks in place on the spline. From this construction it can be seen that when the shaft 245 is shifted toward the right the spline 272 and therefore the disks 275, 278 and 329 are not shifted with the shaft because of engagement of the projection 664 on the spline 272 with the flange 665. On the other hand when the shaft 245 is shifted toward the left the spline and disks are not shifted with the shaft because of engagement of the hub 667 of the disk 275 with the flange 665.

Operation.

It is thought that the above description is sufficient for a complete understanding of the invention, but a résumé of its operation will be given here.

When a ticket is to be issued the chain (Figs. 7^A-7^B) is adjusted to move the destination device, appropriate to the station to which the ticket is to be issued in such position that its rollers 137 (Fig. 12) are in the small tracks 156 (Figs. 7^A and 14). Then the foot pedal 185 (Figs. 1, 6^B and 7^B) appropriate to the class of ticket to be issued is depressed by the foot of the operator. During the initial movement of the foot pedal the links 199 are elevated by the cam edge 198 on the lever 184 to move their projections 204 into engagement with the ratchet wheels 110 (Figs. 6^A and 7^A) and thereby lock the chain in adjusted position. Then the cam slot 189 (Figs. 6^B and 7^B) rocks the lever 177 clockwise to move the slides 167 and 170 (Figs. 14 and 17) and therefore the selected destination device forwardly to an extent dependent upon the foot pedal depressed thereby moving the selected destination device on the tracks 104 (Fig. 11) and 226 (Fig. 25^B) into the printing mechanism. Near the end of the depression of the foot pedal and after the selected destination device has been moved differentially into the printing mechanism the alining arm 207 (Figs. 7^A and 14) is operated by the cam projection 214 (Fig. 6^B) to aline and lock the selected destination device in its moved position. Also near the very end of the depression of the foot pedal the cam slot 590 in the lever 184 operates the lever 587 and through the above described connections releases the operating mechanism.

Near the beginning of the operation of the machine the feeding flanges on the printing and feeding cylinder 339 (Figs. 25^A-25^B and 29^A-29^B) coöperate with the impression roller 340 to feed the ticket strip the length of one ticket. During such movement of the ticket strip the consecutive numbering device prints the total consecutive number of the tickets issued by the machine on the back of the ticket. After the end portion of the ticket strip which is to be the ticket has been fed on the table 343 the frames 350 carrying the platen 230 are rocked clockwise whereupon the knife 338 severs the ticket from the ticket strip and the platen 230 carries the ticket against the selected printing plate 67 on the destination device and against the type carriers to print the destination station, the class of ticket, the fare value and the consecutive number of the tickets of that particular class, on the face of the ticket. Then after the platen has been raised the feeding frame 376 is operated to feed the ticket to the impression

- roll 370 and the cylinder 373 which feed the ticket out of the machine. While the ticket is being fed out of the machine the date wheels 425 (Fig. 29^B) prints the date and 5 the electro plate on the cylinder 373 prints the names of the railroad and issuing station on the face of the ticket. After the ticket has been moved from under the printing platen 230 the platen is again lowered 10 to carry the detail strip 450 against the selected plate 67 and the type carriers 233 and 234 to print therefrom and then the detail strip is fed one step on the storage roll by the feeding mechanism.
- 15 When a foot pedal 185 is depressed the stud 579 (Fig. 40) on the link 596 engages in the notch 606 in the arm 605 thereby holding the foot pedal in moved position. Near the end of the operation of the machine 20 the pin 608 on the disk 607 engages the link 596 thereby rocking the latter to move the pin 597 out of the notch 606, whereupon the spring 182 (Fig. 7^B) for the operated foot pedal restores the latter to 25 normal position. During return movement of the foot lever 185 to normal position the links 199 are lowered to release the chain, the alining pawl 207 (Figs. 7^A and 14) is moved out of alining position, and the lever 30 177 is restored to normal position by the action of the cam slot 183 in the lever 184 carrying the foot pedal to draw the selected destination device back into the chain.
- When it is desired to use the machine to 35 make an audit the frame 618 (Figs. 23^A-23^B, 38 and 39) is slid forwardly to shift the cam shafts 245 and 366 toward the right. During an audit operation the ticket strip is not fed and therefore a ticket is not 40 issued. The frames 350 are operated but once by the cam groove 645 (Fig. 34) to carry the detail strip against the selected plate 67 and the positioned type carriers.
- While the form of mechanism herein 45 shown and described, is admirably adapted to fulfil the objects primarily stated, it is to be understood that it is not intended to confine the invention to the one form of embodiment herein disclosed, for it is susceptible of embodiment in various forms all coming within the scope of the claims which 50 follow.
- What is claimed is:
1. In a machine of the class described, 55 the combination of a plurality of destination devices, means on each destination device adapted to print class designations on tickets, and means for moving the desired device differentially into position to print a designation of the desired class on the ticket.
  2. In a machine of the class described, the 60 combination of a plurality of destination devices, a plurality of printing means on each device for printing tickets of different

classes, and means for moving the desired device differentially so that the desired printing means on the device is in position to print a ticket of the desired class.

3. In a machine of the class described, the 70 combination of a plurality of separate destination devices, a plurality of printing means on each device for printing tickets of different classes, there being one means for each class of tickets, and impression means 75 for carrying the ticket against the desired printing means on the desired destination device.

4. In a machine of the class described, the 80 combination of a plurality of destination devices, means on each device adapted to print the class designations on tickets, means supporting the destination devices and adjustable to move the desired destination device into position to be moved into 85 printing position, and means for moving the selected destination device differentially into printing position so that a designation of the desired class is printed on the ticket.

5. In a machine of the class described, the 90 combination of a plurality of destination devices, a plurality of means on each device for printing tickets of different classes, there being one means for each class of tickets, and a plurality of selectively operable 95 devices, one for each class of tickets, for moving the desired destination device into position to print a ticket of the desired class from the desired printing means.

6. In a machine of the class described, the 100 combination of a plurality of destination devices, means on each device adapted to print tickets of various classes, means supporting the destination devices and adjustable to move the desired destination device into position to be moved into printing position, and a plurality of devices, one for each class of tickets, for moving the desired destination device differentially into printing position 105 to print a ticket of the desired class. 110

7. In a machine of the class described, the 115 combination of a main operating mechanism, a plurality of destination devices, means on each destination device adapted to print class designations on tickets, means supporting the destination devices and adjustable preliminarily to the operation of the machine to move the desired destination device into position to be moved into printing position, and means also operable preliminarily to the operation of the machine for moving the selected destination device differentially into printing position so that the designation of the desired class is printed on the ticket during operation of the machine. 120 125

8. In a machine of the class described, the 130 combination of a main operating mechanism, a plurality of destination devices, a plurality of means on each device for printing class 135

designations on tickets, there being one means for each class, means operable preliminarily to the operation of the machine for moving the desired destination device 5 into position to be moved into printing position, means also operable preliminarily to the operation of the machine for moving the selected device differentially into printing position to print the designation of a class on 10 the ticket from the desired printing means on the device during operation of the machine.

9. In a machine of the class described, the combination of a plurality of destination devices, means on each device adapted to print 15 class designations on tickets, means for moving the desired device into position to be moved into printing position, and means for moving the selected device differentially into 20 printing position to print a designation of the desired class on the ticket.

10. In a machine of the class described, the combination of a plurality of destination devices, a plurality of printing plates on 25 each destination device, each plate being employed to print the name of the destination station and the designation of the class on a ticket, means for moving the desired device into position to be moved into printing position, selectively operable devices, one for 30 each class of tickets for moving the selected destination device differentially into position to print from the desired printing plate.

11. In a machine of the class described, 35 the combination of a plurality of destination devices, means on each device for printing class designations on tickets, a chain carrying said devices, means for adjusting the chain to move the desired destination device 40 into position to be moved into printing position, means for supporting the selected destination device when in printing position, and means for differentially moving the selected destination device out of the chain 45 and on the supporting means so that the designation of the desired class is printed on the ticket.

12. In a machine of the class described, the combination of a plurality of destination 50 devices, means on each device for printing the class designations on tickets, a chain carrying said devices, means for adjusting the chain to move the desired destination device into position to be moved into printing position, means for supporting the selected destination device when in printing position, and a plurality of devices, one for 55 each class of tickets for differentially moving the selected destination device out of the chain and on the supporting means so that the designation of the desired class is printed 60 on the ticket.

13. In a machine of the class described, the combination of a plurality of destination 65 devices, a chain supporting the same, mecha-

nism for adjusting the chain to move the desired destination device into position to be moved into printing position, rollers on said devices, tracks coöperating with said rollers to retain the devices in the chain, and means 70 for moving the desired destination device out of the chain and into printing position.

14. In a machine of the class described, the combination of a plurality of destination devices, a chain supporting the same, means 75 for adjusting the chain to move the desired destination device into position to be moved into printing position, rollers on said destination devices, stationary tracks coöperating with the rollers to retain the devices in the 80 chain, movable tracks with which the rollers on the selected device coöperate, and means for moving the movable tracks to move the selected destination device into printing position. 85

15. In a machine of the class described, the combination of a plurality of destination devices, a chain supporting the same, means for adjusting the chain to move the desired destination device into position to be moved 90 into printing position, rollers on said destination devices, stationary tracks coöperating with said rollers to retain the destination devices in the chain, movable tracks with which the rollers on the selected device co- 95 operate, and means for differentially moving the movable tracks to move the selected destination device into printing position.

16. In a machine of the class described, the combination of a plurality of destination 100 devices, each provided with a plurality of means for printing class designations on the tickets, a chain carrying the destination devices, means for adjusting the chain to move the desired destination device into position 105 to be moved into printing position, tracks for retaining the destination devices in the chain, movable tracks coöperating with the selected destination device, and a plurality of selectively operable devices, one for each 110 class for operating the movable tracks to move the selected destination device differentially into printing position so that the desired means on the destination device prints on a ticket. 115

17. In a machine of the class described, the combination of a plurality of destination devices, a chain supporting the same, mechanism for adjusting the chain to move the desired destination device into position to 120 be moved into printing position, rollers on said devices, tracks coöperating with said rollers to retain the devices in the chain, means for differentially moving the desired destination device out of the chain and into 125 printing position, and means operated by said moving means for locking the selected destination device in its differentially moved position.

18. In a machine of the class described, 130

- the combination of a main operating mechanism, a plurality of destination devices, each provided with means for printing the class designations on tickets, means operable 5 preliminarily to the operation of the machine for moving the desired destination device into position to be moved into printing position, a plurality of levers, one for each class of tickets selectively operable preliminarily to the operation of the machine, means operated by the levers for moving the selected destination device differentially into printing position, and means for locking the operated lever in operated 10 position during operation of the machine.
19. In a machine of the class described, the combination of a main operating mechanism, a plurality of destination devices, each provided with means for printing the 20 class designations on tickets, means operable primarily to the operation of the machine for moving the desired destination device into position to be moved into printing position, a plurality of levers, one for each class of tickets, selectively operable 25 preliminarily to the operation of the machine, differentially inclined slots in said levers, means operated by the slots in said levers for moving the selected destination device differentially into printing position, 30 and means for locking the operated lever in operated position during operation of the machine.
20. In a machine of the class described, the combination of a main operating mechanism, a plurality of destination devices, each provided with means for printing the class designations on tickets, means operable 35 preliminarily to the operation of the machine for moving the desired destination device into position to be moved into printing position, a plurality of levers, one for each class of tickets, selectively operable preliminarily to the operation of the machine, means operated by the levers for moving the 40 selected destination device differentially into printing position, means for locking the operated lever in operated position during operation of the machine, and means operated by the operated lever for alining the selected 45 destination device in its differentially moved position during operation of the machine.

In testimony whereof I affix my signature.
FREDERICK L. FULLER.
